CIRCULAR KNITTING MACHINE

Charles Frederick Manger, George Alfred Buswell,
and Roland Peberdy, Leicester, England, as
signors to The Bentley Engineering Company
Limited, Leicester, England, a British company

Application March 19, 1945, Serial No. 583,560
In Great Britain March 14, 1944

4 Claims. (Cl. 66—50)

1

This invention is for improvements in or relating to circular knitting machines.

Circular knitting machines have heretofore been provided with needle-selecting mechanism for producing pattern and other effects in the knitted fabric by varying the normal operation of selected needles, such for instance as by causing said needles to form floated stitches, tuck stitches or the like, or in a rib-knitting machine, by varying the rib knitting by transferring such needles from one needle cylinder to the other.

Needle-selecting mechanism hereinafter described as illustrative of the present invention is of the type comprising a series of needles, with or without needle jacks or sliders, a cam to operate said jacks or sliders, a series of other elements, hereinafter termed selectors adapted to act upon said needle, jacks or sliders to vary the operative relation of the latter with the said cam, and pattern means for selectively operating the said selectors. The present invention is concerned solely with needle-selecting mechanism of the above type, which mechanism—for the sake of conciseness—is hereinafter referred to as "needle-selecting mechanism of the type described."

An object of the present invention is to provide means whereby the continuity of the patterning over the instep portion of a hose or half-hose will be maintained with greater accuracy than heretofore by a novel method of controlling the needles at the commencement of and during the knitting of the heel portion.

One machine of the nature contemplated by the present invention is described in the specification of prior Letters Patent No. 2,019,396, and in the specific embodiment to be described later and including the improvements according to the present invention a machine similar to that described and illustrated in the said prior specification will be shown.

In the practice of the present invention, pattern is produced by controlling certain of the needles to follow the normal knitting track and at the same time controlling other needles so that they will not clear their loops below the latches of the needles and will in consequence retain their loops at the knitting point instead of casting them over into the fabric as they would do under normal knitting conditions. Such needles may be made to receive the new yarn at the feed point or to miss it entirely thereby producing either tuck stitch or float stitch patterns.

Hitherto, it has been customary at the beginning of the heel to raise all needles (and their associated sliders if present) which are not to be employed in knitting the heel to a height above the normal knitting track where they will remain

2

out of action during the knitting of the heel. For this purpose the needles, or sliders, in the instep half of the machine, are provided with longer knitting butts than those in the heel half and a cam is brought into a position where it raises the long butts only. If this method were adopted in the machine contemplated by the present invention in which patterns are produced in the manner above described, it would not be possible to lower all the long butt needles at the end of the heel and to reselect them according to the pattern before they reach the knitting point, and the continuity of the pattern on the front of the article would be interrupted.

15 According to the present invention, in a circular knitting machine having needle selecting mechanism of the type described, pattern means is provided operative in conjunction with the selectors, when a heel is to be knitted, to select the

20 needles into three groups whereby some are directed into a low non-knitting track, some are directed into a high non-knitting track, and others are permitted to remain in the normal knitting track.

25 Conveniently those needles which are directed into the low non-knitting track are those which, in the last patterning course, had been selected not to knit.

In order that the invention may be more clearly 30 understood one preferred example will now be described with the aid of the accompanying drawings, in which—

Figure 1 is a perspective view of part of a circular knitting machine having applied thereto, 35 one construction of needle-selecting mechanism according to the present invention,

Figure 2 is a plan of certain of the parts shown in Figure 1.

Figure 3 is a sectional elevation of the parts 40 shown in Figure 2,

Figures 4 and 5 are detail views showing, respectively, a jack and a selector in two different positions,

Figure 6 is a detail view of means for operating 45 a selector,

Figure 7 shows a schematic layout of the cam system of the machine,

Figure 8, on an enlarged scale, diagrammatically illustrates the provision of the additional 50 butts on the selectors and the additional operating levers required by the present invention, and

Figures 9 and 10 are sectional views similar to Figure 3 showing a modified means of operating the selectors and modified selectors in two different positions of operation.

Like reference numerals indicate like characters in all figures of the drawings.

The machine illustrated in the drawings comprises a circular bed plate 70 which is secured to the frame of the machine. Above the bed plate 70 and held spaced therefrom by means including pillars 72 is a second bed plate 74 by which the cam box 76 for the lower or plain needle cylinder 78 is supported. The needle cylinder 78 is rotated about its axis by connections from the main shaft of the machine, said connections including a gear wheel 80 (Figure 3) which is attached to the lower end of the needle cylinder 78.

The first of said constructions comprises a pattern drum 82 (Figure 1) located on the outer side of and near the bottom end of the plain needle cylinder 78, and adapted to rotate about an axis parallel with the axis of said cylinder. The pattern drum 82 is rotatably mounted upon a stud 84 (Figure 3) projecting upwardly from a plate 86 secured to the bed plate 70 and comprises an inner core-like portion 88 surrounded by an outer shell 90, the two parts 88 and 90 being secured together by screws 92. The pattern drum is held frictionally against unwanted movement by a spring 94 in compression between two washers 96 and 98 loose on the stud 84, the upper washer 96 being backed up by a nut 100 by the turning of which the degree of compression of the spring 94 can be adjusted. The pattern drum 82 is intermittently rotated by a pawl-and-ratchet mechanism comprising a ratchet wheel 102 (Figure 1) secured to the lower end of the drum, the teeth of which ratchet wheel are engaged by a pawl 104, pivotally mounted upon a lever 106 that can swing about the drum axis and is actuated by a cam 108 carried upon the gear wheel 80. Suitably arranged springs 110 and 112 maintain, respectively, the pawl 104 in engagement with the ratchet wheel 102 and the lever 106 in the path of the cam 108.

The peripheral surface of the pattern drum 82 is adapted to support a number of detachable pins or cam pieces 114 to which end the outer shell 90 of the drum is provided with a number of holes 116 arranged in rows extending around the drum, there being in the present instance fourteen tiers of rows of these holes. In these holes, pins or cam pieces 114 are inserted in accordance with the pattern to be produced in the knitted fabric. Pivoted upon a post 118 (Figure 2) arranged parallel with the drum axis, is a series of spring-pressed levers 120, fourteen in number (see Figure 1) to agree with the number of tiers of holes 116, each of which levers has a pointed end 119 which is located closely adjacent the drum periphery and overlying one of the rows of holes 116; this end 119 of the lever will accordingly be lifted, i. e., moved away from the drum, as the pattern drum rotates, by a cam piece or pieces 114 present in that row. The other end 121 of each lever 120 has a cam incline 122 formed upon it which, when the pointed end 119 of said lever is not lifted by a cam piece 114 in said row of holes is in the path of movement (due to rotation of the needle cylinder) of a butt 123 on a selector 124 in a needle trick 125 in the needle cylinder 78. The selector 124, which will presently be described, is raised by the action of the cam incline 122 on the butt 123. When the pointed end 119 of the lever 120 is lifted by a cam piece 114 on the pattern drum periphery (see Figure 6), the cam incline 122 on the other end of the lever is removed from the path of the butt 123, and consequently the selector 124 is not raised.

A selector 124 is associated with each of the needles 126 (Figure 3) which is concerned in the selecting operation. This selector is located in the needle trick 125 below the usual needle slider 127, but between each slider 127 and the selector 124 there is situated in the trick 125 a jack 128, presently to be described. In general appearance the selectors resemble the usual needle sliders, that is to say they are relatively long and thin pieces of metal adapted to be received in and moved to and fro along the needle tricks in the cylinder. Each selector has two butts 123 and 129 of which the butt 129 is in the same relative position on all the selectors, and is employed to return the selector to an initial position should it have been displaced therefrom in the selecting operation. Thus butt 129 for this purpose is acted upon by a cam 131 on the cam box 76. The second butt 123 of the two butts mentioned is in a different position in different selectors, but in any given selector, the position of this butt 123 is such that when the selector is in said initial position the butt 123 will be engaged by the cam incline 122 on one of the fourteen levers 120, if the pointed end 119 of that lever is not in engagement with a cam piece 114 on the pattern drum. Near its upper end each selector has a short offset portion 132 extending outwardly from the needle cylinder, followed by an upwardly-extending portion 133, the inner side of which (i. e., the side nearer the needle cylinder) has formed upon it an incline which gives to the selector a somewhat pointed upper end 134. This pointed end is adapted to engage and rock a jack 128 which is situated in the trick immediately above the selector. Each jack has two butts 135, 136 adapted to be engaged respectively, by two cam surfaces 137, 138 formed upon a cam block in the cam box 76 of the machine. The two butts 135, 136, on the jack 128 are at different levels, the upper butt 135 extending outwardly and (at times) over the cam surface 137, and the lower butt 136 projecting upwardly in front of the cam surface 138. Below the lower butt 136 the jack slopes downwardly and inwardly in an incline 139 which is adapted to be engaged by the pointed upper end 134 of the selector; and below the incline 139 on the jack, the jack has a short stem 143, rounded at its bottom end, which normally is situated behind the upper end of the selector, in the recess afforded by the offset portion 132 of the selector.

The function of the jack 128 is to raise a needle slider 127 to a level at which it will come under control of the usual cams in the cam box 76 so that the needle associated with the slider will perform its normal operations. To perform this function the jack 128 is raised by the engagement of its upper butt 135 with the cam surface 137, and lifts the needle slider 127 by engagement of the bottom of said slider by the top end of the jack. Having performed this duty, the jack is later returned to its initial position by a third cam surface 141 on the cam block which surface engages a part of the jack between its two butts 135 and 136. When in the selecting operation a needle is not to be lifted as just described, a selector 124 (see Figures 4 and 5) will be raised by the means previously stated, and its pointed upper end 134 will engage the incline 139 on the jack 128 and rock the jack inwardly and remove its upper butt 135 from over the cam surface 137. Later in the operation of the machine the jack is moved outwardly again by the action of the cam surface 138 upon the lower butt 136 of the jack. Centrifugal action due to rotation of the needle

cylinder 78 tends to move the jacks 128 outwardly and thus tends to maintain the upper butt 135 of each jack in full engagement with the cam surface 137. To assist this action the cam surface 137, in cross-section, inclines downwardly and outwardly somewhat, and the lower edge of the upper butt 135 has a corresponding inclination. At the part of the said upper surface 137, however, at which the jack 128 is moved inwardly by the action of its selector, the upper surface 137 of the cam block is substantially horizontal (in cross-section) or even slightly reversely inclined, so as to permit the jack under action of its selector to be moved inward easily at this part of said surface. Immediately following this part of said surface (considered in relation to the direction of rotation of the needle cylinder) the surface rises a distance sufficient to come in front of the upper butt of a jack that has been pushed back by its selector and thus keep that jack in its inward position until it has safely passed the rise on said upper cam surface 137 which is employed to give to a jack its needle-slider-lifting movement. This cam formation, it will be appreciated, completely segregates those jacks which are to remain inoperative from those which are to perform their slider-lifting function.

Among the advantages possessed by a construction according to this invention are the following:

The selectors 124 having only to control the position of the jacks 128 need move but a short distance (say one-sixteenth of an inch) compared with the relatively longer distance (some quarter of an inch) which the jacks have to move to ensure that the needle-sliders 127 controlled by them shall properly engage the cams which act upon the needle-sliders; if by accidental movement of a selector 124 a jack that should not have been acted upon is moved inwardly, so that at least its upper butt 135 only just engages the cam surface 137, centrifugal action and the shapes of that surface and of the butt as aforesaid will move the jack outwardly again so that its butt fully engages said surface; the position in which the pattern drum 82 can be placed is variable within relatively wide limits considering that the point in the needle circle at which the selectors 124 are moved by the action of the pattern drum need not of necessity be closely adjacent the point in said circle at which the jacks 128 act upon the needle sliders 127; and the lay-out of the cam pieces 114 on the periphery of the pattern drum 82 determines which needles shall knit, for, as pointed out hereinbefore, the cam pieces 114 acting on the pointed ends 119 of the levers 120 remove the inclined ends 122 of said levers from the path of butts 123 on the selectors 124 and as a consequence the selectors remain idle, and thereby permit a jack 128 to move its needle slider 127 to a position in which in due course, it reaches the stitch cam.

The two advantages last mentioned are of importance in connection with the multi-feed-point type of machine previously referred to. Thus, in such a machine having two feed points (a main feed point and an additional feed point) a needle-selecting-mechanism according to the present invention can be provided for each feed point. These mechanisms can be placed at any convenient points in the needle circle (usually towards the back of the machine) and each will show by the lay-out of the detachable cam pieces on its pattern drum the needles which are to knit

at the particular feed point to which that mechanism is appropriated.

So far the description follows that already given in respect of the knitting machine described and illustrated in the aforementioned prior Patent No. 2,019,396.

In making a hose, half-hose or the like article having a pattern which extends through the leg and foot, it is necessary to stop the pattern in the heel half of the article at, or a few courses before, the beginning of the heel in order that the heel may be knitted in plain unpatterned fabric. This, in accordance with the present invention is accomplished by the provision on each selector in the heel half of a butt 200 (see Figures 3 and 8) below the selecting butts 123, and provide for co-operation with butts 200, lever 210 to operate on those butts at desired times. The lever 210 will operate similarly to, and will be situated below selector levers 120. At the appropriate times lever 210 is moved into its operative position and lowers all selectors having butts 200, that is to say all selectors which are below those needles that are intended to knit the heel. The horizontal dotted line extending from the top of butt 200 in Figure 8 indicates that when lever 210 is brought into operation the butts will engage the lower sloping face of the lever in order to lower the selectors.

The amount by which the selectors are lowered will be approximately equal to the pitch of the selecting butts 123. When these selectors come to the selecting point some of them will be raised in accordance with the pattern set out but this will have no effect as those which would be so raised will be too low to operate their jacks and will in fact be operated by levers 120 which are situated at positions lower than those which would normally operate on the selectors. The needle jacks will consequently remain in the outward position and all the heel needles will be raised to the knitting track.

The needles in the instep half of the machine which are to be selected not to knit during the last course before the heel, are maintained in the low non-knitting track during knitting of the heel. The selectors for the instep needles are all provided with an additional butt 220 below the normal selecting butts 123 (see Figures 3 and 8) and for these additional butts 220 there is a further additional lever 230, the sloping upper face of which will, when the lever is moved to its operative position, engage beneath the additional butts 220 thereby serving to raise the selectors having those additional butts. Consequently, when lever 230 is operative all the instep needle selectors will be raised and their jacks will be pushed to the inward position so that they will not be lifted by their cams. Consequently any needles in the instep half which are in the low cam track will remain there.

In Figure 7, the main feed point is situated at a position indicated by a line 300 and a second feed point will be situated at the position of line 310. The main stitch cam is shown at 320 whereas cam 330 is the stitch cam for knitting in the reverse direction when making the heel. A stitch cam for the second feed point 310 is shown at 340. The normal knitting track when the second feed point is out of action is indicated by dotted line 350. When knitting is taking place at the second feed point 310, the bolt cam 360 is brought into operation to lower the needles so that they will be engaged by stitch cam 340. Cam 370 serves to raise those needles which have knitted

at the second feed point so that they will consequently follow track 351. During patterning, cam 370 is withdrawn and certain of the needles take the low track 354 whereas the remainder are raised by their jacks (by appropriate pattern selection) and follow track 351. The knitting track for the forward direction of heel knitting is the same as for normal knitting but, in reverse direction the knitting track is indicated by line 352. The instep needles which have been utilised to knit the course immediately preceding the commencement of the heel are raised by cam 380, which engages the long butts only, to the upper idle or high non-knitting track 353. Bolt cams 370 and 398 are withdrawn during all patterning and during the knitting of the heel, and those needles which have not knitted in the course immediately preceding the commencement of the heel will remain in the low non-knitting track indicated by line 354. Cam 400 is fixed so that it misses all short knitting butts but engages long knitting butts. During the knitting of the heel, short butts only are in the knitting track in one direction, and in the reverse direction the short butts are raised by cams 410 and 420. When long butts are raised by cam 410 they are lowered again by cam 400 and so remain in the low non-knitting track 355. Cams 430 and 440 are jack lifting cams and the jacks which are raised by them raise their needles across the gap left by the withdrawal of cams 390 and 370.

A modified form of selector is shown in Figures 9 and 10 by means of which patterning is stopped in the heel portion by providing those selectors 224 which are under the heel needles with longer lifting butts 225 than will be provided for those in the instep half. The lengths of the latter terminate in the position of the dotted line 226. In order to stop patterning a selector lifting cam 227 is moved radially close to the needle cylinder as shown in Figure 9 so that although some of the selectors will be pushed in by the action of one or other of the levers 120 (which in this case are formed to engage the ends of selector butts 228 to press them in instead of to lift them) this will have no effect as regards the long butt selectors as the long butts 225 will still be in a position to be engaged by the lifting cam 227 although the shorter butts 226 will not be so engaged. In Figure 10 the lifting cam 227 is shown as moved a slight distance radially outwards away from the cylinder so that any selectors with either long or short butts that may have been pressed inwardly by levers 120 will now be raised because both long and short butts 225 and 226 will then pass clear of and behind the lifting cam 227. Each of the selectors 224 will be provided with an extra butt 228 which is additional to those required for patterning in order that the same conditions may be achieved as in the case of the previously described construction with the aid of butts 200. These additional butts 228 will be provided on all selectors in the instep half and an additional lever 121 will be provided to co-operate with these additional butts similar in this function to lever 210 of the previously described construction.

When lever 121 is in its operative position, all the selectors in the instep half, which selectors have short butts 226 will be pushed in and will consequently not be raised by cam 227.

We claim:

1. In a circular knitting machine, a needle

cylinder having tricks therein, needles located in said tricks, cam means to effect the knitting motion of said needles, a series of jacks associated with said needles to vary their operative relation with said cam means, a jack-operating cam, a series of selector elements each corresponding to one of said jacks to vary the operative relation of said jack with said jack-operating cam, patterning means to actuate selectively said selectors, and heel-knitting control means to select the needles into three groups for heel-knitting operations, to direct some of said needles into a low non-knitting track, some of said needles to a high non-knitting track and other needles to the normal knitting track, said heel-knitting control means including elements acting through the selectors.

2. The subject matter of claim 1 comprising needle selecting mechanism of the type described, wherein the selectors for the heel and instep needles are provided with butts which are additional to those required for patterning and which are differentiated from one another as between those for the heel and those for the instep needles respectively, in combination with means selectively operated to co-operate with said additional butts at required times for the purpose of group separation of the needles.

3. The subject matter of claim 1 comprising needle selecting mechanism of the type described, wherein the selectors for the heel and instep needles are provided with butts which are additional to those required for patterning and which are differentiated from one another as between those for the heel and those for the instep needles respectively, in combination with means selectively operated to co-operate with said additional butts at required times for the purpose of group separation of the needles, the additional butts

4. The subject matter of claim 1 comprising needle selecting mechanism of the type described, wherein the selectors for the heel and instep needles are provided with butts which are additional to those required for patterning and which are differentiated from one another as between those for the heel and those for the instep needles respectively, in combination with means selectively operated to co-operate with said additional butts at required times for the purpose of group separation of the needles, the additional butts being combined with correspondingly additional selector actuating levers whereby one group of selectors will be raised and the other group lowered by the operation of their associated levers.

45 5. The subject matter of claim 1 comprising needle selecting mechanism of the type described, wherein the selectors for the heel and instep needles are provided with butts which are additional to those required for patterning and which are differentiated from one another as between those for the heel and those for the instep needles respectively, in combination with means selectively operated to co-operate with said additional butts at required times for the purpose of group separation of the needles, the additional butts for the heel needle selectors being of different lengths from those for the instep needle selectors, and the selector actuating cam being movable radially on the machine to engage or miss either one or both sets of butts as required.
